UNITED STATES PATENT OFFICE.

JESSE ALBERT CHADWICK, OF MOBERLY, MISSOURI.

MACHINE FOR GRINDING LOCOMOTIVE VALVE-SEATS.

No. 870,082.

Specification of Letters Patent.

Patented Nov. 5, 1907.

Application filed February 12, 1907. Serial No. 357,090.

To all whom it may concern:

Be it known that I, JESSE ALBERT CHADWICK, a citizen of the United States, residing at Moberly, in the county of Randolph and State of Missouri, have 5 invented certain new and useful Improvements in Machines for Grinding Locomotive Valve - Seats, of which the following is a specification, reference being had to the accompanying drawing.

My invention relates to improvements in machines 10 for grinding the valve-seats of locomotive engines; and the object of my invention is to provide a machine of this character which will prove simple in construction, cheap in manufacture and most efficient in operation.

15 In carrying out my invention I provide two base-blocks which are planed on top and bottom so as to be perfectly true. These are placed in position on the valve-chest of the locomotive. Each base-block carries a slide-block in which are formed holes for the 20 reception of two shafts which extend from end to end of the machine and along which the slide-blocks may be adjusted. On these shafts between the slide-blocks is mounted a grinding-head and a device is provided for adjusting the grinding-head along the 25 shafts. The grinding-head carries a journal-block in which is mounted a rotary shaft one end of which is connected preferably by means of a flexible shaft with any suitable source of power and upon the other end of which is mounted an emery wheel or other suitable 30 grinding device. The grinding-head is formed with suitable guideways in which the journal block is fitted to slide; and a device is provided for raising and lowering the journal-block.

In the drawings illustrating the principle of my invention and the best mode now known to me of applying that principle, Figure 1 is a central longitudinal sectional view, the flexible shaft being shown removed; Fig. 2 is a plan view; Fig. 3 is an end view looking in the direction of the arrow A in Fig. 1; and Fig. 4 is an 40 end view looking in the direction of the arrow B in Fig. 1.

The bottom surface *a* and the ways *b* of the base-block *c* are planed perfectly true. The lower face *a* is formed with a rectangular recess *d* which adapts the 45 base-block to be seated accurately and firmly upon the top of the valve-chest to which it is bolted or otherwise

suitably secured. Upon the ways *b* are mounted slidably the slide-blocks *f*, *f'*, each of which is formed with a rectangular notch *e* in which fits the part *b* on top of the base-block. The ends of the guide-rods *h* 50 are fitted in the apertures *g* formed in the slide-blocks *f*, *f'* and are held therein by the set-screws *i*. Slidably mounted on the guide-rods *h* is the grinding-head *j* formed with the vertical guideways *k* in which is slidably fitted the journal-block *t* in which is journaled the rotary shaft *m* to the end *n* of which is secured the flexible shaft *o* and upon the other end of which is mounted fast the emery wheel *u*. Mounted in the threaded aperture *p* in the top of the grinding-head *j* is an adjusting screw *q* the upper end of which 55 is provided with a hand-wheel *r* and the lower end of which is grooved and in engagement with the lugs *s* formed on the journal-block *t*. By turning the hand-wheel *r* the journal-block *t* and thereby the emery wheel *u* are moved vertically and at right angles to the 60 direction of the guide-rods *h*.

The grinding-head *j* is moved along the guide-rods *h* by means of a threaded rod or screw *w* one end of which engages the face-plate *x* of the grinding-head *j* and the other end of which passes through the threaded aperture *v* in the top of the slide-block *f'*. The outer end of the screw *w* is provided with a hand-wheel *y*.

I claim:

In a machine of the character described, the combination 75 of a pair of base-blocks each formed with ways upon its top; a pair of slide-blocks one mounted on the top of each of said base-blocks; a pair of guide-rods fitted in said slide-blocks and lying in a plane parallel to the ways upon the top of said base-blocks; a grinding-head mounted free to 80 slide along said guide-rods and formed with guideways; a journal-block slidably fitted in said guideways; a rotary shaft mounted in said journal-block; a grinding wheel mounted on said shaft; means for moving said grinding-head along said guide-rods; and means for moving said journal-block vertically at right angles to the direction of 85 said guide-rods; said slide-blocks being movable along the ways on top of said base-blocks horizontally and at right angles to the direction of said guide-rods.

In testimony whereof I have hereunto set my hand this 90 fifth day of February, A. D. 1907, at said Moberly in the presence of the undersigned witnesses.

JESSE ALBERT CHADWICK.

Witnesses:

C. T. RICE,

EDWIN O. DOYLE.
